ANGLE FIXTURE

Edward Hassig, Milwaukee, Wis., assignor to Dependable Engineering Service, Inc., Milwaukee, Wis., a corporation of Wisconsin

Application November 8, 1945, Serial No. 627,355

5 Claims. (Cl. 81—41)

1

The invention relates to a universal fixture whereby a vise, jigs, or magnetic chucks may be supported from a fixed base at any desired angle.

One of the objects of the invention is to provide a fixture of low height yet having considerable range for adjustment in a vertical plane relative to pivotally mounted body portion of the device.

A further object of the invention is to provide a fixture having a three point contact between the body block and the side plates so as to efficiently carry the load imposed on the fixture.

A further object of the invention is to provide a fixture of very sturdy construction in which the body block is pivotally supported at spaced points on the base, side plates are mounted in said body block and vertically angularly adjustable relative thereto, and the vise or fixture mounting plate, which is horizontally angularly adjustable, is firmly mounted on the side plate.

A further object of the invention is to provide simple but effective locks for securing the parts of the device in their adjusted positions.

A further object of the invention is to provide a three angle fixture of simple and rigid construction which may be quickly adjusted to the required angle.

The invention further consists in the several features hereinafter set forth and more particularly defined by claims at the conclusion hereof.

In the drawings:

Fig. 1 is a plan view of a fixture embodying the invention, parts being broken away;

Fig. 2 is a front elevation view thereof, parts being broken away;

Fig. 3 is a horizontal sectional view taken on the line 3—3 of Fig. 2;

Fig. 4 is an end elevation view of the device, parts being broken away and parts being shown in a section taken on the broken line 4—4 of Fig. 1;

Fig. 5 is a detailed sectional view taken on the line 5—5 of Fig. 4;

Fig. 6 is a detailed sectional view taken on the line 6—6 of Fig. 1;

Fig. 7 is a detailed vertical sectional view taken on the line 7—7 of Fig. 3.

Fig. 8 is a detailed vertical sectional view taken on the line 8—8 of Fig. 2, parts being broken away.

Referring to the drawings, the device includes a base member 8, a body block 9, side plates 10, a fixture mounting head 11, and a fixture such as a vise 12.

The base member 8 is a one piece casting hav-

2

ing a flat base portion 13 provided with clamping bolt receiving slots 14 at its ends (only one being shown) whereby the device may be bolted down to the table of a milling machine, drill press, grinder, or other machine tool for holding the work in the desired position, said member having spaced arms or uprights 15 and an index carrying upright 16 adjacent one of the uprights 15.

The body block 9 is a solid steel block having 10 side plate receiving cylindrical recesses 17 milled in its sides and a lengthwise extending bore 18 therein. A transversely disposed sleeve 42 is mounted in the block and provided with a bore 18' of the same diameter as the bore 18, said 15 sleeve having a tight fit in the block. This block 9 is pivotally carried on the uprights 15 by means of a two part spindle formed of two bolt headed shafts 19 and 20 extending through the bores 18 and 18', the threaded solid shank 21 of the shaft 20 19 engaging the threaded sleeve end 22 of the shaft 20 which shafts are journaled in alined bores 23 in the uprights 15, and when drawn up, 25 carry the body block between said uprights with wear washers 24 between said block and said uprights and another washer 25 between one of the uprights and an index plate 26 mounted on the shaft 20 and locked thereto against rotation by a headless set screw 27. The shafts 19 and 20 may be shouldered at 20' as shown, and other forms of spindles, for example a plain through bolt with nut, may be used if desired. The body block is keyed to the shafts 19 and 20 by taper shank screws 9' extending from the base portion of said body block into said shafts and indicated 30 in Figs. 3 and 7.

The index plate 26 has graduations 28 cut or otherwise suitably formed therein running from either side of its center position from 0 to 90° and fixed indicator points 29 having tongue and groove connections 30 with the top surfaces of the upright 16 are secured thereto by socketed head screws 31.

The body block with its spindle support formed by the shafts 19 and 20 is free to swing or pivot 45 in the uprights 15 but may be locked in any desired angular position relative thereto by locks 32 cooperating with said shafts. One of the locks is shown in detail in Fig. 6 and comprises two clamping sleeves 33 and 34 mounted in a vertical 50 bore 35 in the upright and a socket headed bolt 36 passes through the bore in the upper sleeve and has threaded engagement with the threaded bore 37 of the lower sleeve. The sleeves 33 and 34 are disposed on opposite sides of the spindle (either shaft 19 or 20) to be clamped and are curved 55

out, as at 38, where they engage said spindle, so that drawing the sleeves together by tightening up the bolt 36 will firmly clamp the spindle to the upright after the body portion of the device has been set at the desired vertical angular position relatively to the base and in a plane transverse to the axis of said body block. For making fine adjustments while the block is partly locked the spindle portion is usually tapped with a hammer, and for this purpose the top of the plate 26 has impact receiving bosses 39.

The side plates 10 are annular steel plates which fit in the annular recesses 17 in the body block and pivot at 17' on the sleeve 42, so that they can revolve or turn relative thereto and at one side adjacent the end of the block are provided with index markings 40 reading from 0-50° on either side of the horizontal plane passing through the axis of the body block so as to permit angular adjustment of the plates in planes parallel to the pivotal axis of the block, said markings 40 cooperating with a fixed index point 41 on the block. It will be noted that this method of mounting the side plates on the body block provides a multiple point contact between said plate and block since should the plates be out of thrust contact with the sleeve 42 of the block, they may still contact the side walls 43 of the block.

For holding the side plates 10 in the desired angular position, I provide a clamping bolt 44 for each plate, each bolt being mounted in a transverse threaded bore 45 in the sleeve 42, it being noted that the width of the plates are such that the heads of the bolts 44 engage the plates and the ends of the bosses formed by the sleeve 42.

The side plates 10 are rigidly secured together by socket head screw 46, one being shown in Fig. 4, which pass through the fixture mounting head 11 and into the top portions of each of said plates 10. At the same time an index pointer 47 which has a keyed connection 48 with the top portions of the plates and a complementary keyed connection 49 with the bottom portion of the head member 11 is clamped to these parts said connection 49 extending diametrically across said member 11.

The mounting head 11 is a circular metal disk provided with a central threaded aperture 50 and an annular groove 51. The fixture 12 which, for example is herein shown as a vise, is formed from a solid metal block having a circular base portion provided with a cylindrical recess 52 of a diameter to fit over the head 11 and having an annular recess within which a cylindrical index dial 53 has a drive fit, the upper portions of this block being milled out to provide a fixed vise jaw 54 and a companion jaw member 55 in which jaw screws 56 are adjustably mounted. The block also has a bore 57 provided with a counter bore 58 to receive a flat socketed head screw 59 whose threaded shank 60 engages the threaded aperture 50, said screw forming a post about which the vise 12 swivels or turns. For clamping the fixture 12 in any desired angular position a pair of locking nuts 61 are mounted in diametrically disposed slots 62 in the base of the fixture and project over into the annular groove 51 of the head 11 at one side and into curved recesses 63 in the index dial 53 and socketed head bolts 64 mounted in the fixture 12 engage said nuts, and when drawn up, exert a clamping pressure between the nuts and the upper shoulder of the

groove 51 to hold the fixture in clamped position.

It will be noted that the dial ring 53 has degree markings 65 therein running from 0° to 360° and that as viewed in Fig. 2 the side 66 of the pointer 47 cooperates with these markings to determine the angular setting of the fixture.

Instead of the vise, other work holding fixture attachments such as jig mounting plates, magnetic chucks, movable jaw vises may be mounted on the head member 11.

With this construction it will be noted that the body member is adjustable angularly about its pivotal axis, the side plates are adjustable angularly relative to the body plate and in a plane at right angles to the pivotal mounting of the body, and that the fixture member is in turn angularly adjustable relative to the side plates, thus providing a three angle fixture with locks for each adjustment.

I desire it to be understood that this invention is not to be limited to any particular form or arrangement of parts except in so far as such limitations are included in the claims.

- 25 What I claim as my invention is:
1. In a device of the character described, the combination with a base having spaced uprights, a spindle journaled in said uprights, means for locking said spindle in different angular positions relative to said base, a body block mounted on said spindle to turn therewith between said uprights and provided with spaced side recesses, side plates mounted to swivel in said recesses, means for holding said side plates in different angular positions relative to said body block, means for connecting said side plates together, a work holding member supported by said side plates and angularly adjustable in a plane at right angles to the planes of movement of said side plates, and means for locking said member in adjusted angular position.
  2. In a device of the character described, the combination with a base having spaced uprights, a spindle journaled in said uprights, an index plate mounted on said spindle adjacent one of said uprights, a fixed indicator mounted on said base adjacent said index plate, means for locking said spindle in different angular positions relative to said base, a body block mounted on said spindle to turn therewith between said uprights and provided with annular recesses at opposite sides thereof, side plates mounted to swivel in said recesses, means for holding said plates in different angular positions relative to said body block, a head member connected to said side plates, a work-holding member rotatably mounted on said head member and angularly adjustable in a plane at right angles to the planes of movement of said side plates, and means for locking said member in adjusted angular position.
  3. In a device of the character described, the combination with a base having spaced uprights, a spindle journaled in said uprights, means for locking said spindle in different angular positions relative to said base, a body block mounted on said spindle to turn therewith between said uprights and provided with spaced side recesses, side plates mounted to swivel in said recesses, means for holding said side plates in different angular positions relative to said body block, a cylindrical head member connected to said side plates, a work holding member rotatably mounted on said head member in a plane at right angles to the planes of movement of said side plates and carrying an index dial, an indexing pointer having keyed connection with said side plates cooperating with

said dial, and means for clamping said work holding member to said head member in adjusted angular position.

4. In a device of the character described, the combination with a base having spaced uprights, a spindle journaled in said uprights, means for locking said spindle in different angular positions relative to said base, a body block mounted on said spindle to turn therewith between said uprights and provided with spaced side recesses, side plates mounted to swivel in said recesses, means for holding said plates in different angular positions relative to said body block, a cylindrical head member connected to said side plates and provided with an annular groove, a work holding member rotatably mounted on said head member in a plane at right angles to the planes of movement of said side plate and carrying an index dial, an indexing pointer secured to said head member and cooperating with said dial, bolts mounted on said work holding member, and nuts engaging said bolts and having portions projecting into said annular groove to clamp said holding member to said head member in adjusted angular position.

5. In a device of the character described, the combination with a base having spaced uprights,

a spindle comprising bolt headed shafts journaled in said uprights and having threaded connection with each other at their inner ends, means for locking said spindle in different angular positions relative to said base, a body block mounted on said spindle to turn therewith between said uprights and provided with spaced side recesses, side plates mounted to swivel in said recesses, means for holding said side plates in different angular positions relative to said body block, means for connecting said side plates together, a work holding member supported by said side plates and angularly adjustable in a plane at right angles to the planes of movement of said side plates, and means for locking said member in adjusted angular position.
